ATTORNEY

UNITED STATES PATENT OFFICE

OTTO LOOFT, OF TRACY, CALIFORNIA

ADJUSTABLE-HANDLE WRENCH

Application filed November 23, 1929. Serial No. 409,291.

This invention relates to wrenches, and particularly to those of the open ended or so-called solid type, as well as to those of the adjustable jaw or crescent type.

5 The principal object of my invention is to provide a wrench of this general character so constructed that the handle may be adjusted relative to the plane of turning of the wrench and held at any adjusted position. 10 This enables the jaws of the wrench to squarely engage a nut while enabling the handle to be moved out of the plane of the jaws as may be necessary on account of the relative inaccessibility of the nut or on account 15 of obstructions in front of the same. On account of my improved construction the handle may be adjusted so as to avoid any such obstructions, without the necessity of having to use a number of wrenches alternately in removing any one nut, as is sometimes necessary with the one piece or solid construction wrenches as at present used. My improved wrench is therefore more universally adaptable for all-around service 20 than is the present type of wrench.

A further object of the invention is to provide a simple and inexpensive device and yet one which will be exceedingly effective for the purpose for which it is designed.

25 These objects I accomplish by means of such structure and relative arrangement of parts as will fully appear by a perusal of the following specification and claim.

In the drawings similar characters of reference indicate corresponding parts in the several views:

Fig. 1 is a top plan view of my improved wrench.

Fig. 2 is a side elevation of the same showing the handle in its normal position.

Fig. 3 is a similar view partly in section showing the handle as set at an angle to the jaws.

Referring now more particularly to the characters of reference on the drawings, the numeral 1 denotes the jaw member of the wrench having an opening 2 in its outer end shaped as usual to conform to the nut. At the back or opposite to the opening the member 1 is provided with spaced ears 3 between

which the adjacent end of the flat handle 4 projects, and which is pivoted to the ears by a pin 5. Said pin of course extends parallel to the face of the member 1 or transversely of the opening, so that the handle may be turned so as to assume an angle to the plane of turning of the jaw member. The jaw and handle members are arranged adjacent the hinge with suitable means as at 6, so that they may freely turn relative to each other only in one direction from a position in which said members are longitudinally alined with each other.

Projecting outwardly from the member 1 from the face thereof toward which the handle can turn is a lug 7, to which one end of a longitudinally extending screw 8 is pivoted. This screw extends over the pivotal joint and over the adjacent portion of the handle lengthwise thereof and is threaded toward its free end; a thumb nut 9 being mounted on the threaded portion. The nut is turnably confined between the longitudinally spaced ears of a yoke 10 which is partially seated in a recess 11 in the handle and is pivoted onto the handle by a pin 12 extending transversely of said handle or parallel to the pin 5.

By means of this arrangement it will be seen that the jaw member may be maintained square with the nut while the handle is adjusted, by manipulating the nut 9 so as to dispose the handle at any desired angle within certain limits, relative to the jaw member. At the same time the handle when thus adjusted is held rigid with the jaw member so that the necessary pressure may be exerted on the tool without the danger of the handle slipping or moving from its adjusted position.

The hinged end of the handle 4 is cut so as to have tongue and groove engagement with the member 1, as indicated in Fig. 1, so that the rigidity of the handle and jaw members, in a wrench turning direction, is insured or aided by the engaging surfaces of the said members, without depending entirely on the pivotal pin 5.

While I have shown the jaw member as being solid, it will be evident that an adjust-

able jaw head may be employed in connection with the adjustable handle arrangement equally well. Also, while I have particularly shown and described my improved adjusting structure as being incorporated in a wrench, 5 it will be evident that its uses are not limited to wrenches, but that it is applicable to any tool in which adjustment of the handle relative to the work engaging element of the tool 10 may be desirable.

10 From the foregoing description it will be readily seen that I have produced such a device as substantially fulfills the objects of the invention as set forth herein.

15 While this specification sets forth in detail the present and preferred construction of the device, still in practice such deviations from such detail may be resorted to as do not form a departure from the spirit of the invention, as defined by the appended claim.

20 Having thus described my invention what I claim as new and useful and desire to secure by Letters Patent is:

25 In a tool having separate handle and work engaging members, pivot means between said members, a screw extending over the joint between the members at right angles to the pivot, a transverse swivel connection between one end of the screw and one member to prevent longitudinal movement and rotation of 30 the screw, a thumb-nut on the screw, a yoke between the sides of which the ends of the nut are confined, and a swivel connection between the yoke and the other member disposed 35 transversely of the same and of the screw.

35 In testimony whereof I affix my signature.
OTTO LOOFT.
